(57) **CLAIM**

The ornamental design for a utility belt, as shown and described.

DESCRIPTION

FIG. 1 is a perspective view of a utility belt showing my new design;
FIG. 2 is a perspective view of the rear of the utility belt of FIG. 1;
FIG. 3 is a top view of the utility belt of FIG. 1;
FIG. 4 is a bottom view of the utility belt of FIG. 1;
FIG. 5 is a left elevational view of the utility belt of FIG. 1;
FIG. 6 is a right elevational view of the utility belt of FIG. 1;
FIG. 7 is a front elevational view of the utility belt of FIG. 1; and,
FIG. 8 is a rear elevational view of the utility belt of FIG. 1. The broken line showing of environment in the drawings is included for the purpose of illustrating only and forms no part of the claimed design.
